CORNER CUSHION

Carrie M. Reynolds, Rochester, N. Y.

Application April 8, 1933. Serial No. 665,146

2 Claims. (Cl. 5—337)

The object of this invention is to provide a new and improved form of cushion, more especially to be used as a corner cushion for the corner, where the seat, and back and sides come together in a davenport, or an automobile or chair.

Another object of the invention is to make the cushion so that horizontally it will have a triangular cross section, and so that when standing on its bottom it will be inclined rearwardly slightly at the top.

These and other objects of the invention will be illustrated in the drawing, described in the specification and pointed out in the claims at the end thereof.

In the drawing:

Figure 1 is a perspective view of the cushion standing upright.

Figure 2 is a bottom plan view of the cushion.

Figure 3 is a side elevation of the cushion.

Figure 4 is a horizontal section on the line 4x—4x of Figure 3.

Figure 5 is a plan view of the front of the cushion.

Figure 6 is a plan view of the sides or back of the cushion.

Figure 7 is a plan view of the bottom of the cushion.

Figure 8 is a horizontal section through a modified form of the cushion, the section being taken on the same line as is shown in Figure 3.

In the drawing, like reference numerals indicate like parts.

The cover of the cushion is made of three parts or sections, each of which is made of two layers of cloth, the inner layer being a lining and the outer layer being a casing. These sections comprise the front 1, the back 2, and the bottom 3. The front section of the cover of the cushion may be faced or ornamented with any additional cloth desired and the front edge of the cushion cover may be left plain as shown in Figures 1 and 4, or may be provided with a fringe or trimming 4 extending out therefrom as shown in Figure 8.

This fringe preferably is composed of a ribbon braid or fringe suitably inserted along the edge, as indicated at 4. At the back of the cushion cover, the cloth is gathered into a seam 5, which makes a flange extending up and down the back 50 of the cushion for the whole length thereof and serves to stiffen it. A similar flange 6 is formed around the bottom of the cushion cover, where the bottom of the cushion cover is joined to the front and back section, and a similar flange 7 55 is formed around the front of the cushion cover,

where the front and back sections are joined together with the ribbon between them, and at the bottom of the cushion as shown in Figure 1 where the front section of the cover joins to the bottom section of the cover.

The cushion is stuffed or filled preferably with Kapok or any equivalent material.

It will be seen that the finished cushion has four sides, each of which has the shape of a triangle, and when completed and suitably stuffed, the cushion has somewhat the form of a pyramid, which leans backward at the top when the cushion is standing on its base. The cushion is adapted to fill the corner of an automobile seat or davenport seat, and gives a support to the person sitting therein that is otherwise not given by the seat.

I claim:

1. A new and useful article of manufacture comprising a cushion having a cover and a suitable filler therein, said cover having four sides, each side having the shape of a triangle, said cushion being pyramid shaped and tilting back at the top when resting on its bottom in a substantially horizontal plane, and being adapted to fit in the corner of a davenport and furnish a support to a person sitting therein, the front of said cushion slanting forward toward the bottom.

2. A new and useful article of manufacture comprising a cushion having a cover and a suitable filler therein, said cover having four sides, each side having the shape of a triangle, said cushion being pyramid shaped and tilting back at the top when resting on its bottom in a substantially horizontal plane, and being adapted to fit in the corner of a davenport and furnish a support to a person sitting therein, the front of said cushion slanting forward toward the bottom, the back of said cushion cover having a flange formed thereon by a seam at the rear upright edge of the cushion and projecting outwardly therefrom.

CARRIE M. REYNOLDS.
